UNITED STATES PATENT OFFICE.

PETER CLARK, OF NASHVILLE, TENNESSEE.

IMPROVEMENT IN MACHINES FOR CUTTING SHOULDERS ON BLIND-SLATS.

Specification forming part of Letters Patent No. 123,677, dated February 13, 1872.

To all whom it may concern:

Be it known that I, PETER CLARK, of Nashville, in the county of Davidson and State of Tennessee, have invented a new and valuable Improvement in Machines for Cutting Shoulders on Blind-Slats; and I do hereby declare that the following is a full, clear, and exact description of the construction and operation of the same, reference being had to the annexed drawing making a part of this specification, and to the letters and figures of reference marked thereon.

Figure 1 of the drawing is a representation of a top view of my invention. Fig. 2 is a central vertical longitudinal section of my invention. Fig. 3 is a vertical cross-section of the same.

This invention relates to machines for cutting the shoulders and pivots on slats for blinds and the like; and it consists in a combination of old and new devices, producing a machine for that purpose that is easily managed and effectual in operation.

The frame A B C is constructed in the general form shown, and consists of four corner-posts, A'', end ties B, B¹, and B², side rails C' and D D', connected together as shown, and made of wood. A beam, E, preferably of cast metal, rests upon and extends from post to post on each side of the frame, as a support and guide for the two carriages P and P', the one, P', being made fast to the beams by bolts, and the other, P, being movable, and fastened by means of clamps and thumb-screws a and a'. The carriage P is moved and controlled by means of a crank, W, and a long single screw, F, working in female screws cut in lugs b and b' projecting downward from the under side of the carriage. On the tables P and P' are secured, by screws and bolts, the iron frames O¹ and O², which furnish bearings for the punches O, as shown. The punches O are held in place by the caps m and pressed back by the springs n. The bank-heads N, against which the slat presses, by the aid of the screw o² regulates the length of the pivot on the slat. On the screws o² are springs x, to give the bank-head an easy action. On each carriage there are two single shoulder-beds, 4, on which beds the knife-carriages Z operate, and by which they are guided and held in place. The shaft l passes through bearings projecting upward

from the beds 4, and the carriages Z as shown, to serve as a support for the springs l', that tend to throw the carriages Z back, and as a sliding rod for the carriages Z, to which the knives are attached by adjustable set-screws and slots, as shown. On the face of each carriage P P' is bolted an adjustable clamp, 12, which holds the slat in place. The propelling machinery is placed beneath the carriages P P', as shown. Two elbows, A³ and B³, project upward from a central piece which is pivoted in bearings e. To these elbows are pivoted connecting-bars i and g, respectively. The short arm g is attached to the arm h, which is connected to the punch on the fixed carriage P', and the long arm i is perforated, as shown, and pivoted in a slot in an arm, h', which is also perforated, for the adjustment of the arm i. The arm h' is connected with the punch on the adjustable carriage P. Two other elbows, A⁴ and B⁴, project from the central piece, and to their ends are pivoted the arms a'' and b'', which are pivoted to a slotted arm, e, which is pivoted to a short arm, x, that is pivoted to the slotted head of a set-screw, f', in the pedal R, which acts as a lever, having its fulcrum in brackets 6. The punches O are thrust forward by pressure on the pedals, the motion of which is governed and regulated by uprights and set-screws 7, and this leverage regulates the depth that the punches cut the slot and form the pivot on it. The two elbows C³ and C³ are permanently attached to the shafts D⁴ and D⁴, respectively, which are supported in suitable bearings, as shown, that rest on the side frames C¹ and C¹. These shafts D⁴ and D⁴ extend almost the length of the machine. To the upper arm of these elbows C³ are attached two short arms, 8, which are pivoted to arms projecting from knife-carriages Z. The lower arms of the elbows C³ are pivoted to arms p, which are pivoted to plate f, which is pivoted to the slotted head of a set-screw in a lever-pedal, having a fulcrum in brackets on the frames. By this pedal the knife-carriages are moved in a manner like that of the punches. On the shafts are two movable elbows, E' and E', attached to the shafts by two set-screws, K and K. These elbows E' and E' are connected by arms to the knife-carriage on the movable table P. The motion of the pedal communicates to the shafts a rocking motion, which imparts a re-

ciprocating motion to the knife-carriages, thus throwing the knives forward to cut the shoulders on the slat simultaneously at each end of it. This pedal also works between standards, and is adjusted in its motion by a set-screw, which motion determines the depth of the cut or shoulder on the slat. The machine is adjusted to slats of different lengths by moving the carriage P, by loosening the set-screws in the table P, and in the elbows C and C. The shoulders and pivots on the slat are cut and punched alternately, without moving the slat, but by pressing alternately on the pedals.

I claim as my invention—

1. The combination of table P', frame O¹, punch O, bank-head N, beds 4, knife-carriage Z, clamps 12, springs n,² and l', all constructed and arranged substantially as and for the purposes set forth.
2. The combination of the set-screws a and a',

adjusting-screw F, and crank W with the carriages P and P', substantially as and for the purpose specified.

3. The combination of elbows A³ B³ A⁴ B⁴, arms i and g, arms a'' and b'', arm c, arm x, set-screw f', pedal Q, all constructed and arranged substantially as and for the purposes set forth.

4. The combination of elbows C³ and C³, shafts D⁴ and D⁴, arms p, plate f, set-screw and pedal R, adjusting-screw 7, all constructed and arranged substantially as and for the purposes set forth.

In testimony that I claim the above I have hereunto subscribed my name in the presence of two witnesses.

PETER CLARK.
